INTAGLIO PLATE PRINTING MACHINE

William F. Huck, Richmond Hill, N. Y., assignor
to R. Hoe & Co., Inc., New York, N. Y., a cor-
poration of New York

Application November 29, 1938, Serial No. 242,909

8 Claims. (Cl. 101—159)

This invention relates to printing machines in which flat engraved plates are used, and more particularly to machines of this type wherein provision is included to drive a plurality of plate carrying planks successively by and beneath a plate inking unit, a plate wiping unit, and an impression unit.

The principal object of this invention is to improve the structure of this type of printing machine by the provision of means to adjust the chain, or the like, provided to drive the plate carrying planks, and to provide means to adjust the plank guides simultaneously with the chain adjustment.

It is also an object of this invention to provide a printing machine with a chain tensioning means that will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

Figure 1 is a top plan view of a printing machine embodying the features and principles of this invention;

Figure 2 is a side elevational view of the machine shown in Figure 1;

Figure 3 is an enlarged section taken on line 3—3 of Figure 1, to show a chain and guide adjustment;

Figure 4 is an enlarged section taken on line 4—4 of Figure 1;

Figure 5 is an enlarged end elevation of the plate inking unit looking in the direction of arrows 5—5 of Figure 1;

Figure 6 is an enlarged broken section of the inking unit taken on line 6—6 of Figure 1;

Figure 7 is an enlarged partly sectioned end view of the plate wiping unit, the view being taken looking in the direction of arrows 7—7 of Figure 1;

Figure 8 is an enlarged view of a part of the wiping web feeding means looking in the direction of arrow 8 of Figure 1;

Figure 9 is an enlarged section of the wiping

unit reciprocating means taken on line 9—9 of Figure 7;

Figure 10 is an enlarged broken section of the impression unit taken on line 10—10 of Figure 1;

Figure 11 is an enlarged section taken on line 11—11 of Figure 1 to show the impression cylinder driving and controlling means; and

Figure 12 is an enlarged section taken on line 12—12 of Figure 11.

The printing machine shown in the drawings 10 is of a type wherein a plurality of printing plates 11, each mounted on a plank 12 are moved about a base frame 13 to be successively inked, wiped, receive a sheet upon its surface, pass beneath an impression cylinder, or "D" roller, and then have 15 the printed sheet removed therefrom. The base frame 13 is provided with plank supporting and bearing members 14 arranged to provide suitable guiding grooves 15 formed between them, in and by which rollers 16 secured to the underside of 20 the planks 12, one at each corner thereof are guided, whereby the planks 12 are controlled in their movements about the frame 13. A groove 17 also extends about the frame 13 between the members 14. A roller 18 secured to each plank 25 12 by a pin 20, which extends downwardly from the plank into and through the groove 17 is secured to an endless chain 19. The chain 19 is led around sprockets 21, one of which is disposed adjacent each corner of the frame 13. An elec- 30 tric motor 22 of the type which has speed reduction gearing directly associated with it, is connected through a worm 23 and worm gear 24, the gear 24 being secured to the shaft 25 of one of the sprockets 21, to drive this sprocket and the 35 chain 19.

Arrangements are herein shown (see Figures 1, 2, 3 and 4) whereby the chain 19 may be adjusted to maintain it in proper running relation with the sprockets 21 and to simultaneously adjust cooperating plank supporting members 14 on the base frame 13 adjacent the adjusted sprockets, to maintain the grooves 15 and 17 in proper guiding position. The chain and guide adjusting means shown herein includes two stud 40 shafts 26 and 27, upon each of which a sprocket 21 is rotatably mounted. Each of the stud shafts 26 and 27 extends from a cylinder 28 and 29 respectively, which cylinders are rotatably mounted in the base 13. The stud shafts 26 and 27 are 45 eccentric to the cylinders 28 and 29, the arrangement being such that rotation of the cylinders 28 and 29 will move the sprockets 21 carried by the stud shafts 26 and 27, to adjust the chain 19 led around them. Both cylinders 28 and 29 are ar- 50 55

ranged to be adjusted simultaneously by having an arm 31 secured to and extending from each, which arms are connected together at their outer ends by a link 32. A screw threaded bar 33, connected to one end of the link 32 and passed through a lug 34 secured to the base 13 is provided to move the link 32 to swing the arms 31 and rotate the cylinders 28 and 29. The bar 33 may be moved by means of nuts 35 and 36 screw threaded on the bar 33, one at each side of the lug 34.

A bar 37 carried by, and on each of the stud shafts 26 and 27, has each of its ends connected to one of a pair of plates 38 and 39 through blocks 41. The plank supporting members 14, adjacent the eccentrically mounted sprockets 21, are respectively secured to the plates 38 and 39 by screws 42, the plate 38 connecting together all of the supporting members 14 at one side of the groove 17, and the plate 39 connecting together all of the supporting members 14 at the other side of the groove 17. By this arrangement, the rotation of the cylinders 28 and 29 will move the members 14 connected to the plates 38 and 39 simultaneously with any adjustment of the eccentrically mounted sprockets 21. As more clearly shown in Figure 4, the joint between the movable and stationary supporting members 14 is formed by overlapping their ends, as at 43, with the adjacent ends of the stationary ones whereby the sides of the grooves 15 and 17 between these members will not be interrupted.

The mechanism herein shown for applying ink to the plates 11 as they are moved by the chain 19, includes two cooperating fountain rollers 51 and 52, and a plate inking roller 53 (see Figures 1, 2, 5 and 6). The shaft ends 54 and 55 of the fountain rollers 51 and 52 respectively, are journaled in spaced apart uprights 56 and 57, secured to the frame 13 by bolts 60. The fountain rollers 51 and 52 cooperate by being adapted to engage at their opposing faces to form a trough therebetween to hold ink and to act as an ink mill. The trough formed between the rollers 51 and 52 is closed at each end by a V-shaped plate 53 which fits the adjacent peripheral portion of each roller and is spring pressed thereupon by a spring 59, which spring reacts between the upper edge of the plate 53 and a sleeve 61 screw threaded in a lug 62 formed on, or secured to, each upright 56 and 57. The sleeve 61 is provided with a hand wheel 63 by which it may be rotated to adjust the tension of the spring 59. A rod 64 threaded into the top of each of the V-shaped plates extends upwardly through each sleeve 61 to above the hand wheel 63. The rod 64 is engaged by a nut 65 whereby engagement pressure of the plate 53 upon the rollers 51 and 52 may be varied.

The shaft ends 55 of the roller 52 are each journaled in a sleeve 66. The outer periphery of each of the sleeves 66 is eccentric to the axis of the roller shaft end 55, so that by rotating the sleeves 66 the roller 52 is adapted to be adjusted relatively to the roller 51 to vary its engagement therewith, whereby the amount of ink carried past the engaging point from the ink supply will vary. Each sleeve 66 is adapted to be rotated for such adjustment, by means of a threaded rod 67 which is journaled in a lug 68 on the upper side of each upright 56 and 57 and has a hand wheel 69 secured to its other end. The inner end 71 of the rod 67 threadingly engages a part 72 pivoted in an arm 73 extending from the sleeve 66. A sheet metal apron

74 secured at its upper edge to each side of each V-shaped plate 53 extends about the outer side of each roller 51 and 52 and along their entire length to cover these rollers.

The rollers 51 and 52 are power driven from the chain driving motor 22 through a chain 81 led about a sprocket 82 secured on the shaft 25 and which extends to and is led about a sprocket 83 on a vertical shaft 84 journaled in the base 13. The shaft 84 has a bevel gear 85 keyed to its upper end which meshes with a bevel gear 86 keyed to one shaft end 54 of the roller 51. A spur gear 87 secured to the other shaft end of the roller 51 meshes with a spur gear 88 secured to the adjacent shaft end 55 of the roller 52. By varying the size of the spur gears 87 and 88, the relative speeds of the rollers 51 and 52 may be varied. It is preferable that the roller 51 be driven slightly slower than the roller 52. Both sets of bevel gears 85 and 86 and the spur gears 87 and 88 are preferably enclosed in oil-tight housings 89 and 91 respectively, as shown.

The inking roller 53 has each of its shaft ends 92 journaled in a bushing 93, the outer periphery of which is eccentric to the axis of the roller 53. Each bushing 93 is clamped in an arm 94 of a lever 95 by a cap member 96, swingably connected by links 97 to the arm 94 and adapted to be tightened against the bushing 93 by a clamp 98. Each lever 95 is mounted on a stud 99 extending from one of the uprights 56 and 57. Another arm 101 of the lever 95 is acted upon by a spring 102 which reacts between a stud 103 screw threaded into the arm 101, and a lug 104 extending outwardly from each upright 56 and 57. Rotation of the stud 103 varies the tension of the spring 102. The springs 102 constantly act upon the levers 95 to press the roller 53 against the roller 51 whereby it will receive ink therefrom to transfer it to the plate 11. A set screw 105 is threaded through a lug 106 extending from the arm 94 to engage a lug 107 provided on the adjacent upright 56 or 57 to limit the pressure of the roller 53 against the roller 51. By loosening the bushings 93 they may be rotated to adjust the roller 53 relatively to the plate 11 and the roller 51, and to obtain comparative results of such adjustment each bushing 93 is provided with an indicating mark 108 for comparison with a scale 109 provided on each of the cap members 96.

The plate wiping mechanism (see Figures 1, 2, 7, 8 and 9) is adapted to be reciprocated across the plates 11 transversely with respect to their movement about the base 13 by a mechanism 55 which includes spaced apart uprights 111 and 112 which are connected together by a frame member 113 bolted at each end to one of the uprights 111 and 112 by bolts 114. The frame member 113 is provided with a centrally disposed post 115 to which one end of a pitman 116 is secured, by means of a bolt 117. The other end of the pitman 116 encircles an eccentric portion of a sleeve 118 which is rotatively mounted on a stud 119 extending upwardly from a bushing 121 keyed to a vertical shaft 122. The stud 119 is eccentric to the axis of the bushing 121 and to the shaft 122. The sleeve 118 is clamped between the upper surface of the bushing 121 and a washer 123 by a nut 124, which when loosened permits the rotation of the sleeve 118 on the stud 119 to adjust the throw of the pitman 116 and through it the extent of the reciprocating movement of the wiping mechanism. The shaft 122 is connected to an electric motor 126 by suitable gears 75

(not shown) but disposed in a reduction gear casing 125 associated with the electric motor 126.

The spaced apart uprights 111 and 112, and the frame member 113 connecting them, are slidably supported on a pair of spaced apart bars 127 and 128 which in turn are supported at each of their ends from the base frame 13 by posts 129, to which they are secured by bolts 130. Rollers 131 and 132 secured to each side of the frame member 113 and at each end thereof provide anti-friction means between the frame member 113 and the bars 127 and 128, while rollers 133 and 134 each carried on a lug 135 provided on each upright 111 and 112 adjacent each end of the frame member 113 are provided to engage the outer side of each bar 127 and 128 to guide the uprights 111 and 112 and the frame member 113 along these bars with substantially no friction.

The frame member 113 is adapted to carry a cushioning pad 136 and a roller or reel 137 of wiping material preferably a web 138 of paper or fabric. The cushioning pad 136 may consist of several superimposed layers 139 of felt or other suitable material, secured by means of clips 141, which hold the outer layer 139 to a block 142 preferably of wood. A strip or blanket 143 of rubber or other suitable material, is stretched over the outer layer 139 and is secured to the block 142 by spring means such as a plurality of rubber bands 140 secured to the blanket 143 and engaged on pins 144 extending upwardly from the clips 141 at one end of the block 142. At the other end of the block 142 the blanket 143 is engaged directly on the pins 144. The rubber bands 140 maintain the blanket 143 taut over the pad 136, due to their inherent resiliency.

The block 142 is supported on the frame member 113 by four rods 145, one adjacent each corner. The rods 145 are secured to the block 142 by nuts 146 and extend upwardly therefrom through spaced apart lugs 147 and 148 formed on the side walls 149 and 151 of the frame member 113. Each of the rods 145 has a washer 152 secured to its upper end by a nut 153. A spring 154 coiled about each rod 145 reacts between the washer 152 and the top 155 of the frame member 113 to constantly urge the rod upwardly to maintain the upper end of a nut 156 having worm gear teeth on its periphery, threaded on the rod 145 intermediate the lugs 147 and 148, in engagement with the underside of the lug 147. The toothed nuts 156, being threaded on the rods 145, are adapted to adjust the pressure of the pad 136 against the inked printing plate 11 when they are rotated on the rods 145. The toothed nuts 156 are arranged to be rotated by worms 157, two of which are secured to each of a pair of spaced apart shafts 158 which extend lengthwise through the frame member 113, being journaled in each end thereof. A hand wheel 159 is secured on the outer end of each shaft 158 for rotating the same.

Each of the uprights 111 and 112 is provided with spaced apart slotted upstanding arms 161 and 162, in the slot 163 of which a bearing block 164 is slidably mounted. One pair of opposite blocks support the shaft ends of the web roll 137 and the other pair support the shaft ends of a web take-up roll 165 upon which the used web is to be wound. The periphery of the roll 137 rides on a roller 166 from which the web 138 is led to another roller 167. From the roller 167 the web 138 extends under the pad 136 to another roller 168. The web 138 is fed over roller 168

between it and an eccentrically mounted roller 169 and to a roller 171 upon which the roll 165 rides.

A ratchet 172, preferably of the roller type, is secured on one of the shaft ends 173 of roll 165 in position to be operated upon by the usual form of operating device 174, which has a rod 175 extending downwardly therefrom, to rotate the roll 165 to wind the web 138 thereon. A sleeve 176 carried on the upper and long end of a lever 177, pivoted to one side of the adjacent upright 112 by a bolt 178, is slidably mounted on the rod 175. The lower and short end of the lever 177 is connected at 179 to a long link 179, the other end of which is connected by a short link 180 to the other side of the upright 112 (see Figure 8). The link 179 is connected to the bar 181, which extends across and outside of the upright 112, by having a stud 182 extending downwardly therefrom into a block 183 which in turn is pivoted to the bar 181 by a pin 184, the arrangement being such that a universal joint is formed at this point. A pin 185, carried on the link 179 is adapted to engage an arm 186 connected to the shaft 187 of the eccentric roll 169 so as to press it toward the web guide roll 168 when the bar 181 is reciprocated in one direction, herein to the right in Figure 7, so as to cause the web 138 to be gripped between these rolls to prevent it being pulled backwardly by the movement of the planks 12. A spring 188 frees the roll 169 from the roll 168 while the web 138 is being intermittently fed along over the pad 136 by the ratchet 172.

The end of the bar 181, which is broken away in Figure 7, is shown in Figure 8 with its connection to the lower end of an arm 189 that is secured at its upper end to a shaft 191, supported in a bracket 192, mounted on the base 13. The connection between the arm 189 and the end of the bar 181 is similar to that employed between the link 179 and the bar 181 and includes a swivel block 192', forming a universal joint. Another arm 193 is secured to the shaft 191 and has a slot 194 formed lengthwise therein, in which a block 195 is slidably mounted. The arms 189 and 193 with the shaft 191 form a bell crank which is adapted to be rocked by a link 196 connected at one end to the block 190 and at its other end to a crank arm 197 secured to a shaft 198. Adjustment of the block 190 along the slot 194 in the arm 193 will vary the throw of the arm 189 and through the bar 181 vary the action of the ratchet 172 on the roll 165. Adjustment of the block 190 along the slot 194 is obtained by a threaded rod 199 which passes through and threadingly engages a block 195 which by means of a stud shaft 200 is connected to the block 190. The rod 199 is secured to the arm 193 by a lug 200 and has a hand wheel 201 on its outer end by which it may be rotated.

The crank arm 197 is rocked through the shaft 198 by a cam 202 (see Figure 1) secured on a shaft 203 and acting on an arm 204 secured to a vertical shaft 205 journaled in the base 13. The shaft 205 (see Figure 8) extends upwardly through the base 13 and has a bevel gear segment 206 secured thereto in mesh with a bevel gear 207 secured on the crank arm shaft 198. The cam shaft 203 is rotated by a gear 208 secured thereto and which is in mesh with a gear 209 secured on the sprocket shaft 84.

The sheet printing mechanism (see Figures 1, 2, 10, 11 and 12) includes an impression, or "D", cylinder 211, the shaft ends 212 and 213 of which are journaled in frame members 214 and 215 re-

5 respectively. The frame members 214 and 215 are each slidably mounted upon a pair of spaced apart posts 216 and 217, which in turn are slidably disposed in holes 218 provided therefor in the base 10 of the frame 13. The posts 216 and 217 are formed to provide a portion 221, smaller in diameter where they pass through the frame members 214 and 215 than where they pass through the base frame 13, to provide an upwardly directed shoulder 222 upon which the frame members 214 and 215 may seat. A coiled counterweight spring 223, of sufficient tension to support its portion of the weight of the frame members 214 and 215 and the cylinder 211, with their associated parts is disposed about each post 216 and 217, and reacts between the adjacent frame member 214 and 215 and the base frame 13.

15 The lower end of each post 216 and 217 is threaded and has an internally threaded wormwheel 224 operatively mounted thereon. The wormwheels 224 engage a bracket 225 seated against the undersurface of the base frame 13 and are thereby adapted to draw the posts 216 and 217 downwardly against the tension of the 20 counterweight springs, and to adjust the position of the shoulder 222 to limit the downward movement of the frame members 214 and 215 and the cylinder 211. A shaft 226 having a worm gear 227 thereon disposed between the wormwheels 224 on adjacent posts 216 and 217, has a hand wheel 228 (Figure 2) secured upon one of its outer ends whereby all four wormwheels 224 may be simultaneously rotated.

25 A pressure spring 229 is provided, coiled about the upper end of each post 216 and 217 to react 30 between the adjacent frame member 214 or 215 and a bracket 231 extending between the posts in each frame member 214 and 215, to press the frame members downwardly toward the shoulders 222 and maintain a desired pressure of 35 the cylinder 211 against the plate 11 as it passes under the cylinder. A wormwheel 232 is screw threaded upon the upper end of each post 216 and 217 and engages the adjacent bracket 231. 40 Simultaneous rotation of all of the four wormwheels 232 is obtained by means of a shaft 233 having a pair of worm gears 234 thereon, each positioned (as shown in Figure 1), to mesh with two of the wormwheels on the posts in each of 45 the frame members 214 and 215. The shaft 233 has a hand wheel 235 on one of its ends whereby 50 it may be rotated to simultaneously adjust the tension of all of the springs 229 and thereby the pressure of the cylinder 211 on the plate 11.

55 In order to adjust the elevation of the bearings for each end of the cylinder 211 separately, one of the worm gears 234 is preferably provided with a suitable locking device not shown, whereby it may be locked to the shaft 226 in any desired angular relation, and similarly, one of the worm gears 234 may be adjustable with relation to the shaft 233 so that the impression pressure at each end of the cylinder 211 may be separately adjusted.

60 65 A bar 236 extends between the frame members 214 and 215 and another bar 237 extends between the brackets 231 adjacent each of the frame members 214 and 215. The bars 236 and 237 are parallel and are spaced apart, and the upper one 237 has a pressure indicator 238 mounted thereon adapted to be actuated by a pin 239 mounted directly below it on the bar 236, whereby the pressure of the cylinder 211 upon the plate 11 will be indicated.

70 75 Plank back-up rollers 241 and 242 are pro-

vided and are rotatably mounted upon bushings 243 which are in turn mounted upon a stationary shaft 244. The shaft 244 is secured to and is carried in eccentric bushings 245 and 246 which in turn are rotatively mounted in the base frame 13. Rotation of the shaft 244, due to its mounting in the eccentric bushings 245 and 246, as above described, will adjust the back-up pressure of the rollers 241 and 242 upon the plank 12.

80 The cylinder 211 is arranged to be rotated by the chain driving motor 22 (see Figures 1 and 10) from the gear 208 on the cam shaft 203 through a gear 247 in mesh with the gear 208 and secured on a vertical shaft 248, a bevel gear 251 slidably secured on the shaft 248 by a key 249, 15 and a bevel gear 252, adapted to be detachably connected to the shaft end 212 of the cylinder 211 and which is constantly in mesh with the bevel gear 251. The means to detachably connect the bevel gear 252 to the shaft end 212 includes (see Figures 11 and 12) a plate 253 secured to the shaft end 212 by screws 254. A cylindrical boss 255 extends axially from the plate 253 and is provided with a bore 256 in which one end 257 of a shift rod 258 slidably enters. The shift rod end 257 carries a cross pin 259 which extends through the boss 255 in an axially elongated slot 261 provided therein whereby its ends may seat in segmental recesses 262 formed in the rear face of the hub portion 263 formed on the bevel gear 252.

85 A coiled spring 264, reacting between the shift rod end 257 and the bottom of a hole 265 formed in the shaft end 212, is provided to constantly urge the ends of the cross-pin into the recesses 262. A sleeve 266, surrounding the hub portion 263, extends axially therefrom over the ends of the pin 259 to retain it against sliding from the rod 258. The rod 258 is arranged to be axially moved to disengage the ends of the pin 259 from the recesses 262 by being provided with an annular recess 267 in its outer end in which a stud 268 rides. The stud 268 is eccentrically disposed on the end of a shaft 269. The shaft 269 extends through a gear-enclosing and oil-tight casing 271 and has an operating handle 272 secured thereto outside of the casing 271 (see Figures 1 and 2) by which it may be rotated to shift the rod 258.

90 The bevel gear 252 is rotatably mounted upon a sleeve 273 which extends from the cylindrical boss 255. The sleeve 273 extends along the rod 258 beyond the gear 252 and through a brake shoe 276 and a stationary brake plate 277. The brake plate 277 is fastened by bolts 278 to a cover 279 for the casing 271, and the brake shoe 276 is keyed to the sleeve 273 by a key 281 which seats in an elongated slot 282 formed in the sleeve 273. A spring 283 coiled about the sleeve 273 reacts between the brake shoe 276 and a collar 284 abutting the gear 252 to prevent rotation of the cylinder 211 when the pin 259 is disengaged from the gear 252 by manipulation of the handle 272, and at other times presses the pin 259 into the recess 262. The provision of the segmental recesses 262 permits the plate 11 to drive 95 the cylinder 211 faster than it would be driven by the gears 251 and 252, so that the cylinder 211 will run at the same speed as the plate is being driven by the chain 19, to insure clear and distinct printed impressions and perfect registration.

100 Referring now more particularly to Figures 1 and 2, the machine operator will place sheets one at a time from a shelf 285, which is provided and secured to the base 13 for supporting 105

a supply of sheets to be printed, upon a plate 11 as it becomes disposed adjacent station A. After the sheets pass the printing unit under the cylinder 211 and are printed upon by the inked impressions on the plate 11 they are removed from the plate at station B and piled on the shelf 235. The plate 11 is then fed along by the chain 19 past the inking unit where a new supply of ink is applied by the inking roller 53 and then continues about the base 13 to be acted upon by the wiping pad 136 whereby the ink is removed from the surface of the plate 11 and ink is forced into the impressions thereon to completely fill them.

15 As described above, the fountain rollers 51 and 52 of the inking unit are arranged to be adjusted to vary the supply of ink taken by the inking roller 53 to be applied upon the plate 11, and the pressure of the inking roller 53 upon the roller 51 and the plate 11 is also shown to be adjustable. The stroke of the wiping pad 136, whereby it is reciprocated transversely across the plate 11 to thoroughly fill the impressions therein, is shown to be adjustable by means of the eccentric sleeve 118, and the stroke of the ratchet 172 driving the web take-up roll 165 is shown to be adjustable by manipulation of the handle 201 through the threaded rod 199. The pressure of the impression cylinder 211 upon the plate 11 is shown as being adjustable by means of the hand wheels 223 and 235 and the plank back-up rolls 241 and 242 are shown adjustable by means of the eccentric mounting of the shaft 244. The chain 19 may be maintained at proper tension on the sprockets 21 by adjustment of the studs 26 and 27 upon which the sprockets 21 are mounted, certain plank supporting members 14 being simultaneously adjusted to maintain the guide grooves 15 and 17 uninterrupted. A driving motor 22 is shown as adapted to drive operable parts of the various units of the machine by interconnected gearing and to also drive the plates 11 past these units by means of the chain 19.

45 Arrangement is herein shown whereby the planks 12 will be firmly supported as they move about the corners of the frame 13. For instance, referring to Figure 1, as the planks 12 approach the corner of the frame 13 the center roller 18 engages against the arcuate portion 286 of the groove 17 and the rollers 16 are disposed in respect to the grooves 15 as shown by dotted circles in Figure 1. The rollers 16 at opposite corners of the planks 12 engage and are supported by arcuate corners 287 and 288 of the members 14. The planks 13 are therefore firmly supported against rocking movement and are smoothly guided about the corner, the surfaces of the arcuate portion 286 and of the arcuate corners 287 and 288 serving to provide a three point bearing for the planks during their movement about the corners of the frame 13.

55 In view of the inclusion in the structure of a flat plate printing machine of the new and useful features described and particularly pointed out in the claims, a machine is provided which can be maintained at high operating efficiency over a long period.

70 It will be understood that the invention may be embodied in other specific forms without departing from the spirit or essential attributes thereof, and it is therefore desired that the present embodiment be considered in all respects as illustrative and not restrictive.

What I claim is:

1. In a flat plate printing machine, a plate inking unit, a plate wiping unit, a printing unit, a plate carrying plank disposed in a horizontal plane, means to guide said plank successively from one unit to the other, an endless chain to which said plank is connected, sprockets to support the chain, means to drive one of the sprockets, and means to adjust said plank guides and the sprockets to tighten the chain. 10

2. In a flat plate printing machine, a plate inking unit, a plate wiping unit, a printing unit, a plurality of plate carrying planks disposed in a horizontal plane, means to guide said planks successively from one unit to the other, an endless chain to which each plank is connected, a plurality of sprockets about which said chain is led, means to drive one of said sprockets, and means to simultaneously adjust two of said sprockets to tighten said chain. 20

3. In a flat plate printing machine, a rectangular base frame having a substantially flat top surface, a plate inking unit, a plate wiping unit, a printing unit, said units being disposed one at each of three sides of said base frame, a plurality of plate carrying planks slidably seated on said base frame to be moved successively past said units, plank guiding members on said base frame to cooperate with said planks to guide them, a sprocket at each corner of said base frame, a motor to drive one of said sprockets, an endless chain connected to each plank and led about said sprockets, and means to simultaneously move two sprockets and the plank guiding members adjacent the same to compensate for elongation of the chain. 30

4. In a flat plate printing machine, a plurality of units adapted to act in cooperation with a printing plate to print sheets, a plate carrying plank, plank guides extending about said machine past each unit, a plurality of sprockets, a driven endless chain extending about said sprockets to move said plank past each unit, and common means to adjust some of said sprockets and said plank guides to compensate for elongation of the chain. 45

5. In an intaglio plate printing machine, a frame, guideways on the frame adapted to guide a plurality of plate supports through a rectangular path, an endless flexible member adapted to 50 propel the plate supports about said path, means to drive the flexible member, guide members for said flexible member arranged at two adjacent corners of the rectangular path, and means for moving a portion of the guideways and the guiding members to adjust the tension of the flexible member. 55

6. In a flat plate printing machine a plurality of units adapted to act in cooperation with a printing plate to print sheets, a plate carrying plank, plank guides extending about said machine past each unit, a plurality of sprockets, a driven endless chain extending about said sprockets to move said plank past each unit, and means for adjusting the chain by sprocket adjustment to compensate for difference in chain length and to correspondingly adjust the guide. 65

7. In a flat plate printing machine, a plurality of units adapted to act in cooperation with a printing plate to print sheets, a plate carrying plank, plank guides forming a rectangular path about said machine and extending past each unit, a plurality of sprockets, a driven endless chain extending about said sprockets to move said plank around said path, and means for tighten- 75

ing the chain and for adjusting the guide while retaining the rectangular form of the path of the plank.

8. In a flat plate printing machine, a plurality of units adapted to act in cooperation with a printing plate to print sheets, a plate carrying plank, plank guides including a movable plank guide, a plurality of sprockets, a driven endless

chain extending about said sprockets to move said plank along the guides and past each unit, and movable guide and sprocket adjusting means whereby the path of the plank and the path of the chain may be adjusted to compensate for difference in chain length. 5

WILLIAM F. HUCK.
